UNITED STATES PATENT OFFICE.

THOMAS A. TRIBBLE, OF BLOOMINGTON, ILLINOIS.

INDICATOR.

SPECIFICATION forming part of Letters Patent No. 634,485, dated October 10, 1899.

Application filed February 16, 1899. Serial No. 705,644. (No model.)

To all whom it may concern:

Be it known that I, THOMAS A. TRIBBLE, a citizen of the United States, and a resident of Bloomington, county of McLean, and State of Illinois, have invented certain new and useful Improvements in Indicators, of which the following is a specification, reference being had to the accompanying drawings, forming a part thereof, in which similar letters of reference indicate corresponding parts.

This invention relates to improvements in indicators for use of business and professional men as a means for notifying clients or customers of their movements at times when their offices are temporarily closed; and the object of the invention is to provide a device of this class which is so constructed as to be easily read from the outside of a doorway when it is in position on the inside of a frosted or ground glass door.

By the use of this invention all danger of having the device tampered with from the outside is obviated, and it is simple in construction, durable, and inexpensive.

The invention will be hereinafter fully described, and specifically set forth in the annexed claims.

In the accompanying drawings, forming part of this specification, Figure 1 is a front elevation of a door, taken from the outside and having my improved indicator attached to the inside surface thereof. Fig. 2 is a face view of the indicator, illustrated upon an enlarged scale; and Fig. 3 is a sectional plan view taken on the line 3 3 of Fig. 2.

In the practice of my invention I employ, primarily, a transparent plate A, composed, preferably, of mica; but transparent glass may be employed, if desired. This said plate is marked with numerals to form a clock-dial, and ordinary clock-hands B and B' are secured centrally upon the back surface thereof by means of a suitable spindle b. The said plate A is secured within a frame C, comprising the back and front sections c and c', each section having a circular opening c², leading therethrough, and the said openings exactly register with each other to permit rays of light to strike through the transparent plate

A. The frame C is composed of pasteboard or other suitable opaque material, and it is supplied at its upper edge with a string em-

ployed as a means for suspending the device from a nail or hook D, attached to the inner surface of the door.

In the use of the device the same is suspended with its face toward the inner surface of the ground-glass panel e of the door E, and the hands of the clock are set at any arbitrarily-selected time or hour to indicate the time that the user will return to his office, and the face of the plate A is provided with a suitable printed announcement a', such as "Back at" or "Return at." After the hands are properly set the opaque portions of the device, together with the painted inscription thereon, will cast a shadow upon the frosted or ground glass panel, which is distinctly visible from the outside, whereby the customers or clients of the person using the device can readily determine the time of his return, and owing to the position of the device, which is located behind a closed and locked door, it is obvious that mischievous persons cannot tamper therewith and change the relative position of the indicating-hands.

Having thus described my invention, what I claim as new, and desire to secure by Letters Patent, is—

1. As an indicating device adapted for use behind a ground or frosted glass door-panel, the combination of a transparent dial, opaque hands and opaque markings thereon, with an opaque framework surrounding the same, substantially as shown and described.

2. As an indicator for use behind a frosted or ground glass door-panel, the combination of a transparent plate having clock-hands located centrally thereof and a clock-dial and an announcement painted thereon, and an opaque frame with a central opening therethrough surrounding the said dial, and means for suspending the device from the framework of a door, substantially as shown and described.

In testimony that I claim the foregoing as my invention I have signed my name, in presence of two witnesses, this 9th day of February, 1899.

THOMAS A. TRIBBLE.
